UNITED STATES PATENT OFFICE.

JOHN WALENTOWIC, OF VERONA, PENNSYLVANIA, ASSIGNEE OF ONE-HALF TO
STEPHEN MACK, OF OAKMONT, PENNSYLVANIA.

COMBINED FLUE STOPPER AND STOVEPIPE SUPPORT.

Application filed June 30, 1923. Serial No. 648,811.

To all whom it may concern:

Be it known that I, JOHN WALENTOWIC, a citizen of Czechoslovakia, residing at Verona, in the county of Allegheny and State 5 of Pennsylvania, have invented certain new and useful Improvements in a Combined Flue Stopper and Stovepipe Support, of which the following is a specification.

This invention relates to certain new and 10 useful improvements in flue stoppers and stove pipe supports and has for one of its objects to provide a stove pipe support or mounting capable of supporting stove pipes of different diameters without the necessity 15 of providing an entirely new support for differently sized stove pipes.

With the above and other objects in view 20 as the nature of the invention is better understood, the same consists of the novel 25 form, combination and arrangement of parts hereinafter more fully described, shown in the accompanying drawings and claimed.

In the drawings, wherein like reference 30 characters designate corresponding parts 25 throughout the several views,

Figure 1 is a fragmentary front elevational view of a chimney construction showing a stove pipe mounting supported therein with the removable ring members to accommodate stove pipes of different diameters,

Figure 2 is a vertical sectional view taken 35 on line II—II of Fig. 1 showing the stove pipe mounting built into the chimney construction and a baffle associated with the inner end of the mounting for directing smoke upwardly through the chimney and preventing smoke from a lower stove passing outwardly through the stove pipe mounting,

Figure 3 is a sectional view, similar to Fig. 2 showing a modified construction of 40 stove pipe mounting to be positioned in a chimney after construction thereof,

Figure 4 is a fragmentary detail sectional 45 view showing interlocking connections between the ring sections of the stove pipe mounting with a rotatable latch for locking the outer ring in the mounting frame,

Figure 5 is a detail sectional view, similar to Fig. 4 showing a sliding latch for 50 locking the outer ring in the stove pipe mounting, and

Figure 6 is a fragmentary edge elevational 55 view of the inner face of one of the rings showing the bayonet slot connection between

the central disk of the mounting and the several interlocking rings.

Referring more in detail to the accompanying drawings, and particularly to Figs. 1 and 2, and 4 to 6, the reference numeral 1 60 designates a chimney having a side opening 2 therein to accommodate the mounting of a stove pipe support. The support shown in Fig. 2 is placed in position during the construction of the chimney 1 and embodies a sleeve 3 carrying an outwardly directed flange 4 disposed within the chimney flue and a face plate 5 upon the opposite end thereof having the preferred design as illustrated in Fig. 1, the wall of the chimney 70 being constructed between the flange 4 and face plate 5 for permanently securing the stove pipe support in the chimney. It will be seen from each section of Fig. 2 that the stove pipe support is permanently mounted 75 in the chimney construction and is properly retained in position against movement.

The exposed side of the stove pipe support is provided with a relatively large circular opening 6 having a tapering wall 80 within which a plurality of nested rings 7 also of tapering formation in cross section as illustrated in Fig. 2 is received, the inner ring 7 of the group receiving a closure disk 8. An interlocking connection is provided 85 between the several removable rings and the central disk 8 in the form of a bayonet slot connection, pins 9 carried by the periphery of the disk 8 and the several rings 7 with the exception of the outer ring being received in bayonet slots 10 formed in the inner faces of the several rings as clearly illustrated in Figs. 4 to 6, the rings 7 and disk 8 carrying knobs 11 to facilitate positioning thereof.

The connection between the outer ring 7 and the stove pipe support includes diametrically positioned arcuate keys 12 carried by pins 13 journaled in the outer ring 7 and operable from the outer side of the 100 ring by the knobs 13^a, the latch extending from the socket 14 in the ring 7 to the socket 15 in the stove pipe mounting as shown in Fig. 4, and spanning the registering openings 14 and 15 to retain the ring in locked 105 position. The central disk 8 and several rings 7, with the exception of the outer ring are removable from the stove pipe mounting by shifting movements to releasing positions, while the outer ring 7 is removable 110

by rotating the pins 13 through the medium of the handle 13^a to shift the latch 12 from the opening 15 in the stove pipe support to the opening 14 in the carrying ring as illustrated by dotted lines in Fig. 4.

Another form of device for retaining the outer ring 7 in the stove pipe support is shown in Fig. 5 and includes a sliding latch 12^a reciprocable in a socket 14^a formed in the carrying ring 7 and is adapted to be moved into the socket 15^a formed in the stove pipe support, the sliding latch 12^a when positioned as illustrated in Fig. 5 retaining the outer ring in locked condition within the support. It will therefore be seen that stove pipes of various diameters may be properly mounted within the support by removing the center disk 8 and desired number of rings 7, rendering the support universal in its use.

A modified form of support is shown in Fig. 3 wherein the same is adapted to be mounted in the chimney 1^a after construction thereof, an opening 2^a formed in the chimney 1^a and into which the sleeve 3^a of the stove pipe support is positioned. To retain the support positioned in the chimney 1^a, angle members having side legs 16 positioned in engagement with the flue face of the chimney 1^a have the other angle legs 17 thereof engaging the inner face of the support sleeve 3^a to be locked thereto by the fastening devices 18, the angle members operating in lieu of the integral flange 4 illustrated in Fig. 2.

A baffle having a curved outer wall 19, open at its inner and upper sides carries an outwardly directed flange 20 at the inner

edge thereof adapted for engaging the flange 4 upon the stove pipe support and to be secured thereto as at 21, causes upward movement of the smoke passing through the stove pipe support into the chimney and preventing smoke passing upwardly through the chimney from a stove pipe disposed therebeneath from entering the stove pipe mounting and flowing backwardly through the stove. The baffle 19 offers no interference to the proper draft of the stove pipe, but efficiently protects the same from back flow.

While there are herein shown and described the preferred embodiments of the present invention, it is nevertheless to be understood that minor changes may be made therein without departing from the spirit and scope of the invention as claimed.

What is claimed as new is:—

In a stove pipe support and flue stopper, a support embodying a sleeve, and flanges carried by the sleeve with a wall of the chimney construction positioned between the end flanges for anchoring the sleeve in position and a plurality of interlocking rings removably mounted in one end of the sleeve, the connection between the outer ring and sleeve including registering openings in the adjacent contacting faces of the ring and sleeve with the openings bounded by the opposite faces of the ring and sleeve, and a latch positioned in one opening and operable exteriorly of the support for partially moving the latch into the other opening to lock the rings in the sleeve.

In testimony whereof I affix my signature.

JOHN WALENTOWIC.
